CLAIM

The ornamental design for an analysis cartridge top plate, as shown and described.

DESCRIPTION

FIG. 1 is a top perspective view of an analysis cartridge top plate in accordance with the present invention.

FIG. 2 is a top perspective view of the analysis cartridge top plate of FIG. 1.

FIG. 3 is a bottom perspective view of the analysis cartridge top plate of FIG. 1.

FIG. 4 is a top view of the analysis cartridge top plate of FIG. 1.

FIG. 5 is a bottom view of the analysis cartridge top plate of FIG. 1.

FIG. 6 is a back side view of the analysis cartridge top plate of FIG. 1.

FIG. 7 is a front side view of the analysis cartridge top plate of FIG. 1.

FIG. 8 is a right end view of the analysis cartridge top plate of FIG. 1; and,

FIG. 9 is a left end view of the analysis cartridge top plate of FIG. 1.

The broken lines in FIGS. 2-9 and in the middle plate in FIG. 1 depict portions of the analysis cartridge cover plate that form no part of the claimed design. The additional broken lines in FIG. 1 depict environmental subject matter and form no part of the claimed design.

1 Claim, 7 Drawing Sheets
